ASH TRAY

Walter I. Bieger, Minneapolis, Minn., assignor to Arthur Salm Inc., Chicago, Ill., a corporation of Illinois

Filed May 21, 1963, Ser. No. 74,990

Term of patent 14 years

(Cl. D85—2)

FIG. 1 is a top plan view of an ash tray embodying my new design;

FIG. 2 is a sectional view taken on the line 2—2 of FIG. 1;

FIG. 3 is a perspective view;

FIG. 4 is a front elevational view; and

FIG. 5 is a side elevational view thereof, the side not shown being the same in appearance as the side shown.

The dominant features of my design reside in the portions shown in full lines.

The heavy shading in FIGS. 1 and 3 merely indicates a contrasting surface which is substantially flat.

I claim:

The ornamental design for an ash tray, substantially as shown and described.
